(57) **CLAIM**

The ornamental design for a sheath for a hand-held spectrometer, as shown and described.

DESCRIPTION

FIG. 1 is an isometric view of a sheath for a hand-held spectrometer;

FIG. 2 is another isometric view of a sheath for a hand-held spectrometer;

FIG. 3 is another isometric view of a sheath for a hand-held spectrometer;

FIG. 4 is a top view of a sheath for a hand-held spectrometer;

FIG. 5 is a bottom view of a sheath for a hand-held spectrometer;

FIG. 6 is a side view of a sheath for a hand-held spectrometer;

FIG. 7 is another side view of a sheath for a hand-held spectrometer;

FIG. 8 is a front (“head”) view of a sheath for a hand-held spectrometer; and,

FIG. 9 is a rear view of a sheath for a hand-held spectrometer. The broken lines in FIGS. 1-9 are for illustrative purposes only and form no part of the claimed design.

1 Claim, 7 Drawing Sheets
